AWNINg MADE OF METAL PLATES

Salvador Matheus Zveibil, Sao Paulo, Brazil
Application June 12, 1952, Serial No. 293,102

9 Claims. (Cl. 160—62)

My invention relates to improvements in expandable and retractable awnings the roof of which comprises a series of overlapping parallel plates, sections or panels formed of metal or other materials, the awning being suitable for industrial and commercial establishments, industries, storehouses, stations, bus and car terminals, markets, garages and other structures in which an efficient and suitable protection is required against rain and sun.

My present invention is an improvement on the awning structure disclosed in my Patent No. 2,581,827, granted January 8, 1952. The awning of my present invention includes overlapping parallel sections, plates or panels having a structure similar to that disclosed in my patent.

The primary object of my invention is to provide an expandable and contractable awning which is extremely practical and efficient and economical to manufacture.

A further object of my invention is to provide an improved awning structure, in which the series of awning plates or panels are readily extended or contracted and also readily shifted laterally relative to each other and to the supporting structure.

In accordance with my present invention, the improved awning, which may be attached to any suitable supporting structure, includes a series of individual overlapping parallel panels or plates extending outwardly from the supporting structure, when the awning is expanded, these plates or panels being supported by a plurality of spaced expandable and contractable supporting arms extending thereunder and arranged to swing laterally or horizontally from pivot supports so that the series of roof plates or panels may be expanded, contracted or shifted laterally in either direction, or given any combination of these movements simultaneously or independently.

An awning of this type has the advantage that since the supporting arms are pivoted to a supporting means, they may be swung laterally through a considerable arc, up to approximately 180°, thereby greatly enlarging the protection from rain or from the sun's rays.

The improved awning of the present invention is distinguished or characterized by including supporting arms for sustaining the roof plates of the awning made up of pantographically articulated elements, such as rods, plates or other forms of elements which are mounted in a position so that they move in planes parallel to or extending in generally the same direction as the planes of expansion of the roof plates of the awning. The arms comprising the pantographically articulated elements are hinged or pivoted to a supporting means on vertical pivot axes so that the arms can be swung around horizontally in either direction, while at the same time the roof plates supported thereby are maintained in their parallel relationship.

The construction of the awning is such that when the arms are swung in one direction from a position straight out from the supporting structure, the movable roof plates of the awning are shifted in that direction to an extent corresponding to their distance from the pivot axes of the arms. The series of roof plates are also retracted so that the overlap between one plate and the next lower outer plate is increased.

The awning construction of the present invention is such that it may be used completely or partially expanded or open, expanded to any degree and partly shifted or swung so as to provide adequate protection from sunlight as the sun moves in the sky, and completely extended and swung laterally in either direction. Furthermore, the awning can be retracted directly backwards or by a swing sideways.

Other features and advantages of the improved awning construction of the invention are described more in detail hereinafter in connection with the accompanying drawings forming a part of this application and illus-

2

trating a number of embodiments of the improved arm construction.

In the drawings:

Fig. 1 is a perspective view of an awning constructed and arranged in accordance with the invention, the awning being illustrated as partly expanded and mounted on the side of a building over a window;

Fig. 2 is a vertical sectional view through the awning shown in Fig. 1 taken on the line 2—2;

Fig. 3 is a broken plan view of the supporting arm illustrated in Fig. 1, and shown in partially forward expanded condition;

Fig. 4 is a broken sectional view similar to that of Fig. 2 showing the awning in substantially completely retracted position;

Fig. 5 is a broken plan view similar to that of Fig. 3 showing the awning arm of Fig. 3 in nearly completely retracted position;

Figs. 6, 7 and 8 are broken plan views looking down on the awning illustrated in Fig. 1, showing respectively the awning fully extended, partially extended, and almost completely retracted, in straight forward positions;

Fig. 9 is a plan view similar to that of Fig. 6 showing the awning arms fully extended and swung to the left so that the series of awning plates are partly retracted;

Fig. 10 is a plan view looking down on the awning shown in Fig. 1 with the awning arms fully extended and swung fully to the left so that the series of movable awning plates are shifted to the left and moved to fully retracted position;

Figs. 11 and 12 are broken perspective views showing the details of construction of modified forms of pantographic awning arms according to the invention;

Figs. 13 to 17, inclusive, are diagrammatic side elevational views showing various types of awning arm structures in which the pantographically articulated elements forming the arms are made of bars, tubes or plates in various arrangements and forms.

Referring to the drawings, an awning constructed according to my invention comprises a series of parallel movable overlapping plates, lamina or panels 20 extending outwardly from the building or other structure on which they are supported and generally parallel thereto. The panels 20, and an inner similar fixed panel 21, are carried on a plurality of spaced supporting arms 22, two of such arms being shown in Figs. 1 and 6 to 10 of the drawings. The arms 22 are fixed to a horizontal beam 24 carried by spaced brackets 26 attached by bolts 28 to the side of a building 29, or other supporting structure on which the awning is mounted. Each arm 22 comprises a pantographic structure which is pivoted to the supporting beam 24 on a vertical pivot axis which permits the lateral swinging of the arm through a considerable angle.

The roof plate-supporting arms 22 comprise pantographically articulated elements connected or pivoted together by means of vertical pins. These elements are formed from bars, plates, tubes or other conveniently profiled stock, arranged in criss-cross relationship and pivoted together to form a pantographic mechanism having vertical pivot axes and operating in a horizontal plane. The inner end of each pantographic mechanism forming an arm is pivoted on a fixed vertical axis comprising the first pivot joint of the mechanism, such joint being attached to the horizontal beam 24.

The form of arm construction shown in Figs. 2 to 5 comprises a pantographic hinge type structure including a pair of similar plates 30 hinged together at their inner ends on a hinge pin 32. This part of the arm is pivoted by the pin 32 to a supporting bracket member 34 fixed to the beam 24. The outer ends of the plates 30 are hinged respectively to the inner ends of plates 36 and 37, the outer ends of which are hinged together and to adjacent plates 38 and 39 to provide a cross pivot. These plates 38 and 39 preferably form rigid straight continuations respectively of plates 36 and 37.

The arm 22, as shown in Fig. 3, includes a second set of plates 36 to 39 arranged in a cross pivot in the same way as the first set, and final plates 40 and 41 hinged respectively to the outer ends of the outermost plates 38

and 39, the plates 40 and 41 being hinged together at the end by a pivot pin 42. The hinged pantographic structure shown in Fig. 3 includes similar central pivot pins 42 and side hinge or pivot pins 43. The pivoting of the plate sections 36, 37, 38 and 39 to one of the pins 42 to form the cross and at the same time provide a straight rigid connection between plate sections 36 and 38 and between plate sections 37 and 39 may be accomplished in various ways. For example, the pin 42 may carry a plurality of rings, one above the other, to alternate rings of which the adjacent ends of plates 36 and 38 may be welded while the adjacent ends of plates 37 and 39 are welded to the other rings on the pin 42. This will provide a cross hinge at the position of the pins 42 used for hinging and pivoting these plates. The arm 22 may be pivoted to the bracket 34 by means of one or more spaced elements of the bracket bent around pin 32 or by welding the bracket to one or more spaced rings on the pin 32.

In the awning arm construction shown in detail in Figs. 2 to 5, the hinge plates forming the pantographic arm are arranged with their lower edges in the same horizontal plane, while their upper edges slope downwardly and outwardly from the pin 32 in the manner shown in Fig. 2. In other words, the upper edges of the plate sections taper downwardly.

The pins 32 and 42 advantageously extend above the pantographic system and provide bearings for pivotally supporting a bracket or arm 44 for each of the awning plates 20 and 21. Each of these arms 44 includes an upper flat plate or surface 45, as shown in Figs. 3 and 5, tapering to a point at the outer end and a stiffening web or flange 46 (Fig. 2) tapering from the base to the tip of the arm. Each arm 44 is provided at its base with a vertical hole which fits over one of the pins 32 or 42. The plates 20 and 21 may be attached to the arms 44 by means of screws or by spot welding. The lower edge of the flanges or webs 46 preferably extend out horizontally, while the upper surface 45 of the arm slopes downwardly to the desired extent for the roof plates 20 and 21.

The awning roof plates may be made in any form and corrugated if desired but, as shown in Figs. 2 and 4 are flat metal plates having an upturned upper edge 48 and a downwardly turned lower edge 50. The uppermost plate 21 remains in fixed position with respect to the supporting brackets 34 because the pin 32 is not movable, and in certain forms of construction may extend to and be sealed to the wall 29. However, as shown in Figs. 1, 2 and 4, the gap between the wall 29 and the uppermost plate 21 is closed by a plate 52 fixed onto the wall 29 and extending out over the back upturned edge of the plate 21. A single arm 44 is used for supporting one of the plates 20 on each of the arms 22 of the awning and two or more arms 22 may be employed depending upon the dimensions of the awning and the rigidity of the awning plates 20.

The pantographic arm structure of the present invention may be made up in various ways not only from the standpoint of the elements of construction but from the standpoint of the appearance of the awning. One form of construction has been described above in connection with Figs. 1 to 5 of the drawings. Fig. 11 illustrates a modified form of supporting arm construction in which the elements of the pantographic system are made up of plates 54 of uniform width mounted horizontally to provide a pantographic system of the type shown in Figs. 2 to 5. In Fig. 11 the inner central pivot of the system includes a pivot pin 55 to which the supporting bracket corresponding to the bracket 34 is pivoted, this pin being relatively long and including a fixed bearing member 56 on which one of the plate-supporting arms 46 is carried. The other central pivot pins for supporting the awning plates extend progressively less above the pantographic plates 54 in order to provide for the slope of the awning. One of these pins 57, provided with the fixed bearing ring 56 is shown in Fig. 11. At the outer end of the pantographic arm the bearing ring 56 on the pin 57 may be omitted or rest directly on the end plates of the arm as in Fig. 2. In all of the forms of arm construction, the center row of pins on which the plate supporting arms 44 are pivoted move in a straight line when the arms are expanded and contracted.

The modified form of construction shown in Fig. 12 illustrates the use of tubes, rods or bars 58 and 59 for forming the pantographic arms. In this instance, the

elements of the pantographic system include a progressively decreasing number of tubes, rods or bars from the inner to the outer end of the arm. Fig. 12 also shows a modified form of pivot pin and plate-supporting construction in which the center row of pins 60 are bent to provide forwardly extending arms 61 to which the awning plates may be fastened, these arms 61 taking the place of the arms 44 shown in Figs. 2 to 5. The effective height of the pins 60 above the horizontal lower plane of the pantographic arm progressively decreases from the inner to the outer end to provide for the desired slope of the awning. The laterally extending portions 61 are inclined to the desired extent to provide the desired slope for the individual plates. It is to be understood that the outer ends of the arms 61 will at the same time extend slightly above the next succeeding arm and the plate attached thereto. The combined pin 60 and arm 61 may be used in most forms of the pantographic arm.

Figs. 13 to 17, inclusive, show diagrammatically further modified forms of awning arm construction. In Fig. 13, the pantographic arm is made up of tubes, rods or bars 62, the arm being wider at the inner end than the outer and having a horizontal base. The upper part of the arm is stepped at the position of the awning plates, so that each plate supporting arm 44 is pivoted in with the elements forming the next section to the rear, the outermost plate being supported on an arm 44 pivoted in the end pivot of the pantographic arm along with the tubes, rods or bars.

30 The form of arm construction shown in Fig. 14 is somewhat similar to that shown in Fig. 12, except that the elements of the pantographic arm are made up of tubes, rods or bars 64 to form an arm of uniform height and extending parallel. The set of pivots are the same as in Fig. 11, except that the plate supporting arm 44 for the outer awning plate is pivoted in the same manner as in Fig. 13.

The arm structure shown in Fig. 15 is generally the same as that shown in Fig. 2 in that it is wider at the inner end than at the outer and the upper portion slopes according to the slope of the awning. On the other hand, the lower edge of the arm, which is made up of metal plates 66 hinged together, slopes downwardly from its inner fixed end to its outer end, thereby giving a somewhat different appearance from that of the arm structure shown in Fig. 2.

The awning arm shown in Fig. 16 is a pantographic arm made up of metal plates 68 hinged together as in Fig. 2 to form a pantographic mechanism. In this instance, the plates are of uniform width so that the upper and lower edges of the arm are parallel and arranged to provide a continuous slope corresponding to the desired slope of the awning. In Figs. 15 and 16, the awning plate-supporting arms are mounted in the same manner as in Figs. 2 to 5.

The pantographic supporting arm structure shown in Fig. 17 comprises elements made up of rods, bars or tubes 70, and has an upper structure the same as that shown in Fig. 13. The lower portion of the arm, however, is stepped at each of the center pivot joints and at the first outside pivot joints to provide a distinctly different appearance from that of the arm structure shown in Fig. 13. In Fig. 17, the plate supporting arms 44 are pivoted to the pantographic arm in the same manner as in Fig. 13.

65 The awning of the present invention is expandable and retractable straight out from the supporting structure by reason of the expandable and retractable feature of the pantographic arms, as illustrated in Figs. 6, 7 and 8 of the drawings. The awning may be expanded or contracted to the position shown in Figs. 6, 7 and 8 or shifted to the position shown in Figs. 9 and 10 by means of a pole carrying a hook, not shown, which may be engaged into the eye of an eye-bolt 72 attached to one or all of the arms of the awning, as shown in Fig. 2. When 75 the awning is extended fully by expanding the pantographic arms, as in Fig. 6, the awning plates 20 may be shifted laterally to either side by swinging the ends of the pantographic arms either to the right or to the left, these arms being adapted to swing through an angle of approximately 180° as will be seen by comparing the showing in Fig. 10 with that in Fig. 6. It will be noted, however, that Fig. 10 illustrates a second method of retracting the awning plates, by swinging the arms 22 completely to the right or left. Fig. 9 illustrates the awning 80 with the arms fully extended and the plates 20 shifted

partly to the left so that the awning will be more effective to the left of its normal position as shown in Fig. 6, for example.

The shifting of the awning plates 20 to one side or to the other of the position shown in Fig. 6 is possible because of the parallel arrangement of the arms 22 and the pivoting of the plates each at a single pivot point with respect to each arm so that the pivot points of all arms are arranged in parallel. The arms 22 of the awning are tied together in parallel relation by the plates 20 and when the arms are swung sidewise on their vertical pivots, for example, on the pivot pins 32, the plates maintain their parallel relationship with respect to each other and to the supporting structure, but they are shifted in accordance with the movements of the plate-supporting pivot pins carried by the awning arms. When the awning plates are completely collapsed, as in Figs. 4, 8 and 10, sufficient space is available under the plate supporting arms 44 or 61 to accommodate the next lower plate as it is moved back.

Where the awning is placed over a window as illustrated in Fig. 1 of the drawings, for example, the plates 20 may be moved for a part of the morning to one side of the window and for a part of the afternoon to the other side of the window in accordance with the direction of the sun's rays.

Means not shown in the drawings may be provided for retaining the awning arms in any of the positions illustrated in the drawings or in any other desirable position or condition. Such means may comprise a suitable latching means for holding the pantographic arms in any extended, partially extended, or completely retracted position. Similarly, means may be provided for latching one or more of the arms in any laterally swung position, such as those illustrated in Figs. 9 and 10 of the drawings. Since such means form no part of the present invention they are not illustrated.

The awning plates illustrated in the drawings constitute one form of plate, but it is to be understood that other forms of plates or panels may be employed and that any size, shape, or number of plates may be used to provide the overlapping relationship shown in the drawings. This overlapping relationship permits a free combined forward and lateral movement which is substantially without friction and which provides at the same time an ideal protection from the sun and rain. The plates themselves may be made of aluminum, plastic, glass or other available material, but it is to be understood that where the plates are relatively long, three or four supporting arms may be provided.

In the awning construction shown in Figs. 1 to 5 of the drawings, the awning is illustrated as being supported on a beam 24 of circular cross-section held in spaced supporting brackets 26. The beam 24 is rotatable in the brackets 26 and may be held against rotation by means such as a bolt or pin.

If desired, the beam 24 may be rotated on its axis, in order to regulate the inclination of the awning or to permit the swinging of the awning down to a vertical position so that it can serve as a closure or shutter for the window or other space protected by the awning. Where the awning is intended to be used for this purpose, as at certain times of the year, the beam 24 may be provided with a ratchet and pawl device associated with one of the brackets 26 and means for rotating the beam 24 so that the awning may be readily swung to the desired angle.

Having thus described my invention, what I claim is:

1. In an awning for attachment to a supporting structure including a series of individual rigid overlapping parallel roof plates arranged to extend generally parallel to the supporting structure on which the awning is to be mounted, a plurality of spaced parallel arms by which said plates are supported, said arms being arranged to extend outwardly from the supporting structure, each arm comprising pivoted elements forming a pantographic system for expanding and retracting the awning, a supporting means for said arms arranged to be attached to the supporting structure, the inner end of each arm being pivotally attached to said supporting means on an axis permitting the lateral swinging of said arms, and a roof plate-supporting means pivoted to each arm for supporting each plate thereon, all of the plurality of plate supporting means for each plate being similarly pivoted to the respective arms, whereby the plates of said series are maintained in parallel relationship during the expansion and con-

traction of the awning arms and during the swinging of said arms on their pivot axes for the purpose of laterally swinging the awning plates with respect to each other.

2. In an awning for attachment to a supporting structure including a series of individual rigid overlapping parallel roof plates arranged to extend generally parallel to the supporting structure on which the awning is to be mounted, a plurality of spaced parallel arms by which said plates are supported, said arms being arranged to extend outwardly from the supporting structure, each arm comprising pivoted elements forming a pantographic system for expanding and retracting the awning, the elements of the pantographic system being pivoted on vertical pivot pins and being movable in planes at right angles to the pivot pins, a supporting means for the inner ends of said arms arranged to be attached to the supporting structure, and a roof plate-supporting means pivoted to each arm for supporting each plate thereon, said roof plate supporting means being pivoted to said arm on an axis extending in substantially the same direction as the axes of said pivot pins, all of the plurality of plate-supporting means for each plate being similarly pivoted to the respective arms, whereby the plates of said series are maintained in parallel relationship during the expansion and contraction of the awning arms.

3. An awning as claimed in claim 2, in which the plate-supporting means carried by said arm is respectively pivoted on the projecting portions of said vertical pivot pins.

4. An awning as claimed in claim 2 in which the pantographic system of each arm includes side and center rows of vertical pivot pins, the center row of which is movable in a straight line when the arm is extended and retracted, the pivot pins of said center row of pivot pins projecting beyond the arm at their respective positions, 35 the plate supporting means for the roof plates being respectively pivoted on the projecting portions of said center row of pins.

5. An awning as claimed in claim 2, in which the pantographic system of each arm includes side and center 40 rows of vertical pivot pins, the center row of which is movable in a straight line when the arm is extended and retracted, the pivot pins of said center row of pivot pins extending beyond the arm and forward at their respective positions and constituting the said roof plate-supporting means for the roof plates.

6. An awning as claimed in claim 2, in which the pantographic system of each arm extends through a greater height at its inner end than at its outer end.

7. An awning as claimed in claim 2, in which the support for the arms is rotatable for varying the inclination of the awning.

8. An awning as claimed in claim 2, in which the elements of the pantographic system are selected from the group of elements consisting of plates, rods, bars and tubes.

9. In an awning for attachment to a supporting structure including a series of individual rigid overlapping parallel roof plates arranged to extend generally parallel to the supporting structure on which the awning is to be mounted, a plurality of spaced parallel arms by which said plates are supported, said arms being arranged to extend outwardly from the supporting structure, each arm comprising pivoted elements forming a pantographic system for expanding and retracting the awning, the elements of the pantographic system being pivoted on vertical pivot pins and being movable in planes at right angles to the pivot pins, a supporting means for the inner ends of said arms arranged to be attached to the supporting structure, said supporting means including means by which the inner end of each arm is pivotally attached to said support permitting the lateral swinging of said arms, and a roof plate-supporting means pivoted to each arm for supporting each plate thereon, all of the plurality of plate-supporting means for each plate being similarly pivoted to the respective arms to maintain the plates of said series in parallel relationship during the expansion and contraction of the awning arms and during the swinging of said arms on their pivot axes for the purpose of laterally swinging the awning plates with respect to each other.
